US0D1095829S

(12) **United States Design Patent** (10) **Patent No.:** **US D1,095,829 S**
(45) **Date of Patent:** **** Sep. 30, 2025**

(54) **TIP PROTECTOR**

(71) Applicant: **Raine Medical, Inc.**, Grand Rapids, MI (US)

(72) Inventors: **Gabrielle Kelly**, Alto, MI (US); **Kristi Schelhaas**, Jenison, MI (US)

(73) Assignee: **Raine Medical, Inc.**, Grand Rapids, MI (US)

(**) Term: **15 Years**

(21) Appl. No.: **29/969,503**

(22) Filed: **Oct. 22, 2024**

(51) **LOC (15) Cl.** **24-99**

(52) **U.S. Cl.**

USPC **D24/231; D24/147**

(58) **Field of Classification Search**

USPC D24/107, 108, 111, 119, 127, 128, 130, D24/133, 146, 147, 151, 173, 217, 227, D24/231; D8/403, 499

CPC A61M 5/3202; A61M 5/3273; A61M 25/0618; A61M 2005/325

(57) **CLAIM**

The ornamental design for a tip protector, as shown and described.

DESCRIPTION

FIG. 1 is a perspective view of the tip protector showing our new design.

FIG. 2 is a front view of the tip protector of FIG. 1.

FIG. 3 is a rear view of the tip protector of FIG. 1.

FIG. 4 is a left side view of the tip protector of FIG. 1.

FIG. 5 is a right side view of the tip protector of FIG. 1.

FIG. 6 is a top view of the tip protector of FIG. 1.

FIG. 7 is a bottom view of the tip protector of FIG. 1; and, FIG. 8 is another perspective view of the tip protector of FIG. 1.

The broken lines in the figures show portions of the tip protector that form no part of the claimed design.

1 Claim, 8 Drawing Sheets
